CLAIM

The ornamental design for a wireless ultrasound device, as shown and described.

DESCRIPTION

FIG. 1 is a top perspective view of a wireless ultrasound device showing my new design;

FIG. 2 is a top perspective view thereof;

FIG. 3 is a bottom perspective view thereof;

FIG. 4 is a left side view thereof;

FIG. 5 is a right side view thereof;

FIG. 6 is a rear view thereof;

FIG. 7 is a front view thereof;

FIG. 8 is a top view thereof; and,

FIG. 9 is a bottom view thereof.

The features shown in broken lines in various Figures are for illustrating environmental structure and form no part of the claimed design.
